UNITED STATES PATENT OFFICE.

CHARLES K. GILES, OF CHICAGO, ILLINOIS.

LINING FOR WATCH-CASES.

SPECIFICATION forming part of Letters Patent No. 293,861, dated February 19, 1884.

Application filed September 13, 1883. (No model.)

To all whom it may concern:

Be it known that I, CHARLES K. GILES, a citizen of the United States, residing at Chicago, in the county of Cook and State of Illinois, have invented a new and useful Improvement in Linings for Watch-Cases, which is fully set forth in the following specification, reference being had to the accompanying drawings, in which—

10 Figure 1 represents a plan view of a hunting-case watch containing my improvement, with the front plate open. Fig. 2 represents a vertical section of the same closed, taken on the line $x x$; Fig. 1, on an enlarged scale; Fig. 15 3, an elevation of the lining detached; Fig. 4, a vertical section of the bezel detached; Fig. 5, a similar view of the back cap detached.

My invention relates to an improvement in watch-cases of ordinary construction, either 20 the hunting-case or open-faced; and it consists in providing a lining of special construction for such cases, the improvement being enclosed within the lining.

I will proceed to describe in detail the construction of my improved lining and the mode of applying it to the case, and will then point out definitely in the claim the special improvement which I believe to be new and wish to protect by Letters Patent.

30 In the drawings I have shown the improvement applied to the hunting-case A, which may be of any ordinary construction, consisting of a center, a , to which is hinged a front plate, a' , and a back plate, a'' , in the usual way. A metallic ring or band, B, is made to fit closely 35 the center of this case and of sufficient depth to accommodate the movement which this band is adapted to receive, being provided near its front edge with an inside seat or rabbet, b, on which the edge of the front plate of the movement rests when placed within the band. This band is also provided with an exterior screw-thread, b' , at its front edge, and a similar thread, b'' , at its back edge. The bezel C has a crystal, D, mounted in the usual way, and is provided with an internal screw-thread, c, as is shown in Fig. 4 of the drawings, whereby the bezel is adapted to be turned on the front portion of the band. The back cap, E, is also provided with an internal screw-thread, e, whereby it is adapted to be turned on the back portion of the band. The bezel is preferably made

of the same material as the case, in order to make an appropriate finish for the watch when set up.

In applying my improvement to the case, the movement is first placed within the band and fastened therein by any suitable device. The bezel is then screwed to the band, and the latter, with the movement, dropped into the center, which it closely fits. The back cap is then screwed onto the band, and thereby the front and back are drawn down tightly upon the center, so as to make perfectly tight joints and hold the parts securely together, as shown 65 in Fig. 2 of the drawings. If the watch is to be stem-winding, the band must of course be perforated to receive the winding-stem, and if key-winding the back cap must be perforated to receive the key. A slight notch may 70 be made in the inside of the easing at the proper point along the seat for the movement, into which a pin on the latter drops, thereby keeping the movement from turning in the band, and this is the only fastening device absolutely 75 necessary in the application of my improvement, as above described, to secure all the parts and retain them in their proper position.

It will be seen at once that with this improvement I obtain a complete lining for the case, which completely incloses the movement and protects it from injury. The construction provides tight joints in all places, so that the movement is protected from dust in a manner 85 substantially perfect, the linings being made in different parts, all of which are connected together by screw-threads. These parts are readily detached whenever occasion requires, and at the same time the fitting of the case is 90 made so close and tight as to hold the lining firmly in place, as above described. I thus am enabled to provide a hunting-case watch in which the case for the movement is dust-tight and water-tight, and I am not aware that 95 this has ever been successfully accomplished before my invention, although I am aware that it has been frequently attempted.

This improved lining may also be applied to an open-faced watch with the case of ordinary construction. In such application, the crystal may be mounted in the bezel, as described above, in which case the front plate would be reduced to a simple ring closing down

around the bezel; or the crystal may be mounted in the front ring as usual, which then becomes the bezel, and the part C will then be made as a plain ring, which screws down on the lining and extends over the center on the outside, and the dial on the inside holding these parts in just the same manner as described above. My object is in this improvement to provide a lining for a case of the usual construction without being compelled to change the case in any essential feature.

I wish it understood that in the present application I do not claim anything contained in my prior applications filed May 31, 1883, and June 13, 1883, or my application filed of even date herewith for an "improvement in watch-cases."

Having thus described my invention, what I claim as new, and desire to secure by Letters Patent, is—

A lining-band for a watch, adapted to receive the movement, and provided at each edge with a threaded section, in combination with a "ring" case-center closely and accurately fitting the outside of the lining-band, a screw bezel or ring adapted to be turned on the front edge of the band, a screw back cap adapted to be turned upon the back edge of the band, and front and back case-pieces hinged to the center and adapted to be closed upon the latter outside of the bezel and back cap, whereby the case may be accurately adjusted to the lining and securely clamped in place, and the box formed by the lining, bezel, and back cap inclosed within the hinged portions of the case, substantially as and for the purposes set forth.

CHARLES K. GILES.
